(57) **CLAIM**

The ornamental design for a dosing closure, as shown and described.

DESCRIPTION

FIG. 1 is a front and left-side perspective view of a dosing closure embodying my new design, the dotted lines representing an exemplary canister and forming no part of the inventive design;

FIG. 2 is a front and left-side perspective view of a dosing closure embodying my new design;

FIG. 3 is a front elevational view thereof, the rear elevational view being a mirror image;

FIG. 4 is a right-side elevational view thereof;

FIG. 5 is a top plan view thereof; and,

FIG. 6 is a bottom plan view thereof.

1 Claim, 2 Drawing Sheets

FIG. 4

FIG. 5

FIG. 6
